UNITED STATES PATENT OFFICE.

EMIL FRANKE, OF LONG ISLAND CITY, NEW YORK.

PEDAL ATTACHMENT.

1,204,000.

Specification of Letters Patent.

Patented Nov. 7, 1916.

Application filed March 28, 1916. Serial No. 37,331.

To all whom it may concern:

Be it known that I, EMIL FRANKE, a citizen of the United States, residing at Long Island City, in the county of Queens and State of New York, have invented new and useful Improvements in Pedal Attachments, of which the following is a specification.

This invention relates to pedal pads.

In such machinery or mechanism where a controlling foot pad is employed, the serious objection arises of the surface of the pedal becoming worn and rendered smooth so as to prevent the foot from taking the proper purchase thereon during the operation of depressing the pedal. It is this objection that I aim to eliminate.

In view thereof, I have devised a pedal pad consisting of a yieldable body having means thereon for detachable connection with the pedal, the said means serving to expose the upper surface of the yieldable body so as to permit the foot of the operator to be brought in direct contact therewith.

In view of the many different shapes of pedals, I have devised a peculiar and novel form of clamp which is used in connection with the pad and adapted to be adjusted therefrom whereby to accommodate itself, respectively to all sides of the pedal, irrespective of the shape thereof.

I aim also to employ a pedal pad including a clamp consisting of adjustable elements having normal pedal clamping or gripping portions and terminal actuating bendable portions which may be brought into clamping engagement with the pedal after the normal portions have been brought into engagement therewith.

With the above and other objects in view which will appear as the nature of the invention is better understood, the same consists in the improved construction and novel arrangements of parts which will herein-after be fully and particularly pointed out in the claim.

In the accompanying drawings, has been illustrated, a single and preferred form of the invention, it being, however, understood that no limitation is necessarily made to the precise structural details therein exhibited, but that changes, alterations and modifications within the scope of the claim may be resorted to when desired.

In the drawings:—Figure 1 is a plan view of my improved pedal pad showing it applied to one type of pedal. Fig. 2 is a simi-

lar view showing the pedal pad applied to another type of pedal. Fig. 3 is a perspective view of the clamp and associated detachable elements. Fig. 4 is a sectional view taken on the line 4—4 of Fig. 1.

The pad consists of a main body plate 1, having a superposed cushioning block or yieldable body 2, mounted thereon and confined thereagainst by lugs 3, which are bent up from the marginal edges of the plate and lugs 4 which are also bent up from the marginal edges of the plate and the last mentioned lugs are preferably terminally bent as at 5, and then extended into radial recesses 6, in the cushioning body. This last mentioned arrangement provides means whereby the cushioning body may be readily removed from the plate when worn and a new body substituted therefor at a minimum cost. In addition thereto the angular extensions 5, co-act with the side walls of the recesses 6, so as to hold the cushioning body against turning upon the plate 1, when pressure of the foot is applied to the body. The upper surface of the body may be ribbed, or otherwise suitably formed so as to maximize the gripping tendency of the body against the foot when depressing the pedal. As a further means of confining the body to the plate 1, spurs 7, are upstruck from the plate within the marginal edges thereof and said spurs are embedded in the pedal 2 or made to suitably penetrate a part of the body as shown.

In order that the pad may be made to accommodate itself to a pedal of most any well known shape, I employ a clamp which consists of identical arcuate gripping elements 8, which are preferably arranged in sets of two. These elements are formed of metal and each is provided with a normal hook shaped clamping portions 9, and normal plate combined actuating and gripping or clamping portions 10. The elements are so arranged upon the plate 1, that the portions 10, of the respective elements are disposed in relatively close proximity in pairs, respectively at diametrically opposite points to the body or block 2. This arrangement is preferred for the sake of convenience in the operation of moving the several normal clamping portions 10, into engagement with the adjacent sides of the pad as will be fully understood. The said normal plate actuating portions 10, are bendable and after said portions have served the purpose of

means to permit the normal portions 9, to be adjusted to their clamped positions upon the pedal, they too are bent to form hooks 11, which are very similar in design to the normal hooks 9, and in this manner, they are made to effectually grip the sides of the pedal. The elements 8, are freely slideable upon the plate 1, in upstruck guides 12, formed on the plate as shown.

10 From the construction described, it follows that the normal clamping portions of the elements 8, may be moved substantially in a radial direction and they may be made to very nicely accommodate themselves to 15 the next adjacent sides of the pedal, irrespective of the shape of the pedal, after which the normal plate terminals of these elements may be made to clamp against the remaining sides of the pedal. The points of

gripping contact of the clamping elements 20 are equi-distantly arranged upon the plate 1, so as to provide uniformity in the gripping action of the device against the pedal.

What is claimed as new is:

A device as described comprising a plate 25 having guides located within its edge, pliable metal grippers held upon the plate by guides and having end portions extending beyond the edge of the plate, said plate also having lugs located at its edge and adapted 30 to hold a cushion.

In testimony whereof I affix my signature in presence of two witnesses.

EMIL FRANKE.
